Horace T. Fleisher

BY

Frank J. Busser

ATTORNEY.

UNITED STATES PATENT OFFICE.

HORACE T. FLEISHER, OF PHILADELPHIA, PENNSYLVANIA.

APPARATUS FOR TRANSFERRING KNITTED FABRIC.

1,184,089.

Specification of Letters Patent.

Patented May 23, 1916.

Application filed February 4, 1916. Serial No. 76,142.

To all whom it may concern:

Be it known that I, HORACE T. FLEISHER, a citizen of the United States, residing at Philadelphia, county of Philadelphia, and 5 State of Pennsylvania, have invented a new and useful Improvement in Apparatus for Transferring Knitted Fabric, of which the following is a full, clear, and exact description, reference being had to the accompanying drawings, which form a part of this specification.

In the manufacture of ribbed topped hosiery the ribbed top is first knitted on a machine and taken off; it is then placed on a 15 transfer ring or quill ring and transferred to a machine which knits on the leg and foot portions. The ribbed top is looped on the transfer ring by hand. Great difficulty is experienced in this operation due to the 20 smallness and great number of stitches, each of which must be placed on an individual quill of the transfer ring. The operation is rendered much more tedious and difficult in transferring black or gray tops, it being al- 25 most impossible to distinguish the stitches from the quills and other parts of the transfer ring.

The object of my invention is to overcome this difficulty by means of a light so placed 30 and directed as to shine through both the quills of the transfer ring and the fabric and form a contrast between the fabric and the quills so as to make the individual quills and stitches stand out and be easily distin- 35 guishable and so modified as to avoid causing any glare or injury to the eyes of the operator. I accomplish this object by a construction and arrangement a preferred embodiment of which is shown in the accom- 40 panying drawings wherein—

Figure 1 is a vertical sectional view of my invention attached to an ordinary transfer ring cup. Fig. 2 is a horizontal sectional view of Fig. 1.

45 *a* represents an ordinary cup used for holding a transfer ring *b*.

c is any convenient support for the transfer ring cup *a*.

50 *d* is an ordinary bolt to fasten the transfer ring cup to its support.

e is a plate of glass of any desired color (preferably green) fitted to the base of the

transfer ring cup *a* and fastened to said cup at suitable points *f*.

g is a cylinder of any light metal, fitted 55 to the cup *a* and fastened at suitable points by means of ears *h* and screws *i*.

j is a base for an electric light socket *k*, adapted to fit into and close the lower end of the cylinder *g*. 60

l is an ordinary electric light bulb within the cylinder *g*.

In practising my invention the light *l* is turned on and the transfer ring *b* placed in the cup *a*. The light is directed by the cylinder *g* so that it shines through the glass *e* upon the quills of the transfer ring and the work placed thereon, in such a manner that the quills and stitches are easily distinguishable. At the same time the light is so modified and softened as to cause no strain upon the eyesight of the operator. 70

It is found that by the employment of my invention an operator working on black or gray goods can, at a substantially lower 75 rate of pay on a piecework basis, earn more money than when carrying on the transferring operation without the aid of my invention. The saving to the manufacturer is found to be great enough to substantially 80 enlarge his margin of profit.

Having now fully described my invention, what I claim and desire to protect by Letters Patent is:

1. The combination with a support adapt- 85 ed to receive a transfer ring, of a source of light, means whereby said light is directed upwardly toward said support, and a me- dium adapted to modify the light rays interposed between the source of light and the 90 position occupied by the quills of the trans- fer ring.

2. The combination with an annular sup- port adapted to receive a transfer ring, of a source of light arranged to direct light rays 95 upwardly through the opening in said sup- port, and a medium, adapted to modify the light rays, extending across the opening in the support.

3. The combination with an annular sup- port adapted to receive a transfer ring, of a source of light, an inclosure secured to and depending from said support and adapted to restrain the diffusion of the light rays, and 100

a medium applied beneath the support and extending across the circular opening therein and adapted to modify the light rays passing upwardly therethrough.

5 4. The combination with an annular support adapted to receive a transfer ring, of a source of light, an inclosure secured to and depending from said support, a base secured

to said inclosure, a lamp secured to said base, and a light modifying medium applied beneath the support and extending across the opening therein. 10

In testimony of which invention, I have hereunto set my hand, at Philada., Penna., on this 2nd day of February, 1916.

HORACE T. FLEISHER.
